UNITED STATES PATENT OFFICE.

HARRY C. NEWMAN, OF PORTLAND, OREGON, ASSIGNOR TO NEWMAN AIR COUPLER COMPANY, OF PORTLAND, OREGON.

AUTOMATIC COUPLING.

1,009,554.

Specification of Letters Patent. Patented Nov. 21, 1911.

Application filed January 7, 1911. Serial No. 601,257.

To all whom it may concern:

Be it known that I, HARRY C. NEWMAN, a citizen of the United States, and a resident of Portland, in the county of Multnomah and State of Oregon, have invented a new and Improved Automatic Coupler, of which the following is a full, clear, and exact description.

This invention relates to automatic couplers for the train pipes of air-brake systems, signal pipes, and steam pipes of railroad trains, and has reference more particularly to a device of this class, comprising heads adapted to be arranged in juxtaposition to effect the operative connection of the pipes which are associated with the heads, one of the pipes associated with each head forming a supporting means therefor, in combination with means controlled by the movement of the last-mentioned pipe, for operating the valves of the various pipes.

The object of the invention is to provide a simple, and efficient coupler for use in connection with railroad and other cars, by means of which the steam pipes, the train pipes of the air-brake system, and the signal pipes, can be automatically coupled when the cars are coupled or secured together, in which the valves are controlled by the movements of the coupler parts, but in which the play or slack of the car coupler will not affect the operation of the valves, in which the washers rendering tight the connections between the pipe sections can be easily changed or replaced, in which the valves are automatically closed when the coupler parts are disengaged and are automatically opened when the coupler parts are brought into juxtaposition, and in which the valves are left open when the car coupling is accidentally broken, in order to set the brakes of the cars.

The invention consists in the construction and combination of parts to be more fully described hereinafter and particularly set forth in the claims.

Reference is to be had to the accompanying drawings forming a part of this specification, in which similar characters of reference indicate corresponding parts in all the views, and in which—

Figure 1 is a side elevation of an embodiment of my invention showing certain of the parts broken away and in cross section; Fig. 2 is a horizontal section on the line

2—2 of Fig. 1, showing certain of the automatic coupler parts in plan; Fig. 3 is a front end view of the coupler, showing the same associated with a car coupler, parts of the latter being broken away and in cross section; Fig. 4 is a rear end elevation of one of the coupler members; Fig. 5 is a fragmentary plan view showing two of the coupler parts in juxtaposition; Fig. 6 is an inverted plan view of part of a car coupler showing a safety device associated therewith and used in connection with my automatic coupler; Fig. 7 is an enlarged, fragmentary cross-section showing part of a coupler head, and illustrating the means for permitting the removal of a washer or gasket; Fig. 8 is an inverted plan view showing a detail of construction; and Fig. 9 is a longitudinal section on the line 9—9 of Fig. 8.

Before proceeding to a more detailed explanation of my invention, it should be clearly understood that the present form of the device constitutes an improvement upon the coupler shown in my United States patent application filed June 4, 1910, under Serial No. 564,988. While my coupler can be so constructed that any one of the pipes can be used as the supporting means for each coupler part, I prefer to employ the steam pipe which supplies steam from the engine to the various cars, for heating purposes and the like. This pipe carries the head of each coupler unit, and is suitably guided in hangers or brackets associated with the corresponding part of the car coupler. The steam pipe is preferably located in an insulating casing of any suitable form. However, these and others of the details of construction, shown for example herewith, form no part of the invention, and can be varied in accordance with individual preference and special conditions, without departing from the underlying spirit of the invention.

Referring more particularly to the drawings, I have shown for example, one member 10 of a car coupler of the usual construction, comprising a draw-bar having a head 11 at which is pivotally mounted by means of a pin 12, a jaw or locking member 13. The lower end of the pin 12 has secured thereto an eccentric disk 14, the pin being held in position by a set screw 12^a. A stop 15 is movably mounted, by means of a stud 16, 110

upon the head 11, and is pivotally connected by means of a pin 17 with the eccentric disk. The stop has a slot 15^a which receives the end of the stud 16. It also has at the free end a laterally disposed finger 18, and constitutes a safety device for a purpose which will appear hereinafter. Hangers or brackets 19, having at the upper ends laterally disposed parts 20, are secured by means of bolts 21, 10 or in any other suitable manner, under the coupler 16. They are tightly connected at their lower ends by means of a bolt rod 22. Each hanger has an opening 23 in which is located a cylindrical casing 24. The latter 15 preferably has an insulating lining 25 within which is located a steam pipe 26.

The casing 24 and the steam pipe 26 are movable relatively to the brackets 19. At each end of the casing is a head 27, through 20 which the corresponding end of the steam pipe section 26 projects. One end of the steam pipe section has secured thereto an elbow 28, and the other has associated therewith a valve 29 which communicates with 25 the main section 30 of the steam pipe. The valve has an operating arm 31. A link 32 is pivotally secured by means of a pin 33, at one end, to the forward bracket 19. The link at the opposite end has an enlargement 34, provided with a slot 35, which receives a stud or projection 36 mounted upon the end of the valve arm 31. The projection 30 has a laterally extended head, so that it cannot become disengaged from the slot and the 35 enlarged head 34 of the link.

A collar 37 is rigidly secured by means of set-screws 38 or in any other suitable manner, upon the casing 24. A helical spring 39 is movably arranged upon the casing, and at one end engages the collar 37, and at the other end engages the rear bracket 19. The spring tends to hold the coupler element in a normal, projected position, such that the valve 29 is open. Secured in openings of the rear bracket 19, are 40 valves 40 and 41 having respectively, operating arms 42 and 43. These are operatively connected by means of links 44 and 45, with the collar 38, the links being pivotally secured thereto at the ends, by means of pins 46. The links 42 and 43 have enlarged, slotted ends 47, by means of which they are loosely connected with the respective valve arms, as is the case with the link 50 48 and the valve arm 31. The valves 40 and 41, respectively, control the air, brake train pipe 48 and the signal pipe 49. The valves are connected by means of couplings 55, with the flexible pipe sections 51.

55 The elbow 28 is connected by means of a coupling 52, with the coupler head 53. Each head comprises a tapered socket 54 and a tapered nose 55, having at the end a reduced, pointed part 56 adapted to fit into a 60 corresponding end opening 57 of a socket

54. It will be understood that the heads are similar, so that as the nose of each head rides into the socket of the other head, the two parts are guided into juxtaposition, to effect the coupling. Each head has three 70 passages 59 therein, respectively, for the air, the steam, and the signal system. Each head has a pair of inlet couplings 58, at which are secured the ends of the flexible pipe sections 51, which connect the heads 75 and the air and signal pipes. The steam passage of the head is connected with the steam pipe, through the coupling 52 and the elbow 28. The passages 59 of the head have outlets 60 at the face thereof adjacent to 80 the opening of the socket 54. Each outlet is provided with a rubber or other suitable gasket 61. These gaskets are of annular form, and each has a laterally extended flange 62 which engages at a corresponding, 85 inwardly disposed flange 63 at the outlet 60, so that the gasket is secured in place. The head has a plurality of bores or openings 64 which intersect the passages 59, and in which are removably received plugs 65, each 90 having a right-angle passage 66 communicating with one of the passages 59 and an outlet 60. The plugs have threaded parts 67 which are received in corresponding, 95 threaded portions 68 of the openings 64. Each plug has a head 69 permitting its manipulation by means of a wrench or other suitable implement. Gaskets or washers 70 are received in annular enlargements 71 of the openings 64.

100 With each coupler element or unit I employ a comparatively stiff, but fairly resilient rod or bar 72, having at one end an offset part which is secured in a recess or opening of the head by means of a set-screw 73. The rod is located in suitable openings of the brackets 19, and serves to support the head, to hold the same in position and prevent it from sagging or swinging unduly. When the heads of the coupler units or elements are in juxtaposition, the tapered parts 55 are in place within the sockets, and cause the heads to press against each other, so that the gaskets at the outlets of the passages are in juxtaposition. In this way the 105 passages are connected, and the joining of the outlets is a tight one, whereby the escape of steam, or air, or other fluid under pressure is obviated. When the coupler parts are brought together, the coupler elements are forced rearwardly, against the tension of the springs 39, as it will be remembered, they are normally projected, that is, they are projected when not engaged. The movement of the coupler elements opens 110 the various valves, so that the fluids under pressure can flow through the pipes and the couplers. When the parts are uncoupled, the various valves are correspondingly 115 closed.

Upon the elbows 28 are ribbed, upwardly disposed projections 74, each adapted to engage the loosely disposed end 18 of a stop 13 when the same is forced into its path. 5 Should the train coupler become broken accidentally, the tearing loose of the jaw 13 will tend to force the stop into the path of the projection 74, so that as the coupler elements are disengaged, the projections will 10 abut against the stops and prevent the springs 39 from projecting the coupler elements. Consequently, the valves will all remain open and the brakes will at once be set, to bring the separated cars or parts of a 15 train to a stop, automatically.

Having thus described my invention, I claim as new, and desire to secure by Letters Patent:

1. A device of the class described, comprising a pair of coupler elements having heads adapted to be arranged in juxtaposition, and each including a pipe section in communication with its head, means for slidably supporting said heads by means of said 25 pipe section, additional pipe sections communicating with said heads of said elements, said heads having passages therein adapted to communicate when said heads are in juxtaposition, said pipe sections having 30 valves, and means for controlling said valves by the movements of said elements.

2. A device of the class described, comprising a pair of coupler elements having heads adapted to be arranged in juxtaposition, and each including a straight pipe section in communication with its head, means for movably supporting said pipe sections whereby they can slide in the directions of their lengths to support said elements mov- 40 ably, additional pipe sections communicating with said heads of said elements, said heads having passages therein adapted to communicate when said heads are in juxtaposition, said pipe sections having valves, 45 means for controlling said valves by the movements of said elements, and springs normally projecting said elements into positions such that said valves are closed.

3. A device of the class described, comprising a pair of coupler elements, pipes associated therewith and adapted to communicate when said elements are in juxtaposition, means for supporting said pipes whereby said elements have limited free- 55 dom of movement in longitudinal directions, valves controlling said pipes, means whereby said valves are closed when said elements are disconnected, and springs normally projecting said elements into positions such that said valves are closed when said elements are disconnected.

4. A device of the class described, comprising a pair of coupler elements, pipes associated therewith and adapted to com- 60 municate through said elements when the

latter are in juxtaposition, means for slidably mounting said pipes in position to support said elements movably each of said elements having a head provided with a socket and a tapered part adapted to receive said 70 socket of said other element, valves controlling said pipes, an operative connection between each of said valves and one of said elements, whereby when said elements are in predetermined positions said valves are 75 closed, and springs tending to hold said elements in positions such that said valves are closed, whereby when said elements are brought into juxtaposition, said springs are compressed, to permit said valves to be 80 opened.

5. A device of the class described, comprising a pair of movably mounted coupler elements, pipes associated therewith and adapted to communicate when said elements 85 are in juxtaposition and each having a valve, and operative connections between said valves and said elements, said connections permitting a limited freedom of movement of said elements when operating said 90 valves.

6. A device of the class described, comprising a pair of movably mounted coupler elements, pipes associated therewith, means whereby said pipes communicate when said 95 coupler elements are in juxtaposition, valves controlling said pipes, and links operatively connecting said valves and said elements, whereby the latter serve to operate said valves, said links being loosely connected 100 with said valves, whereby said elements have a limited freedom of movement without operating said valves.

7. A device of the class described, comprising a pair of movably mounted coupler 105 elements, pipes associated therewith, means whereby said pipes communicate when said coupler elements are in juxtaposition, valves controlling said pipes and each having an operating arm provided with a stud, and 110 links for operatively connecting said valves and said elements, whereby the latter serve to operate said valves, each of said links having a slot movably receiving one of 115 said studs.

8. A device of the class described, comprising a pair of movably mounted coupler elements having heads adapted to communicate when said elements are in juxtaposition, pipes having flexible connections with said elements and rigidly mounted, further pipes communicating with said elements and movable therewith, said pipes having controlling valves, operative connections between said valves of said first-mentioned 120 pipes and said elements, and operative connections between said valves of said further pipes and fixed points, whereby the movements of said last-mentioned valves serve to operate the same. 125 130

9. The combination, with a car coupler, of a train pipe coupler having a valve controlling the flow of fluid through said train pipe coupler, and a spring tending to project said train pipe coupler into position such that said valve is closed, said car coupler having a safety device including a stop, adapted to hold said train pipe coupler in position against the tension of said spring, whereby said valve is maintained open if said car coupler is accidentally released.

10. The combination, with a car coupler including a movable jaw, and a pin for holding said jaw in place, of a train pipe coupler having a valve controlling the flow of fluid through said train pipe coupler, and a spring tending to project said train pipe

coupler in position such that said valve is closed, a stop connected with said pin and normally held thereby in an inoperative position, said train pipe coupler having a lug adapted to engage said stop when the latter is in an operative position, to hold said train pipe coupler in place against the tension of said spring, whereby said valve is maintained open if said car coupler is accidentally released.

In testimony whereof I have signed my name to this specification in the presence of two subscribing witnesses.

HARRY C. NEWMAN.
